PROCESS OF ERECTING LARGE SPAN BUILDINGS

Michael A. Fouhy, Brooklyn, N. Y.

Application March 10, 1944, Serial No. 525,860

1 Claim. (Cl. 189—1)

This invention relates to parabolic or other curved roofs, including the so-called bow-string type, and aims to permit the construction of integrally formed and mutually merged combination roofs and sides of buildings. This invention is particularly applicable to buildings of large span. By the term "large span" is meant a span of twenty-five feet or more.

Another object of the invention is the provision of flexible members or girders or the like, wherein the top and bottom elements are held together in spaced relationship by means of webbing or lacing, these members being made sufficiently flexible so that they may be readily bent, curved, or arched into the desired form at the building site or elsewhere. When erected, the top element becomes a structural part of the roofing and the bottom element forms part of the ceiling of the building.

A further object of the invention is to provide a novel combination of fabrication and erection wherein each member's component parts are assembled on the site without previously having been curved and are then curved during the process of lifting the members into place, advantage being taken of the material sag of the member's ends while the member is being lifted by its middle. The member is then maneuvered into position, after the sagged ends are drawn inward and downward by means of the rigging, and is fastened into its final position in the structure.

The above and other objects will become apparent in the following description, wherein characters of reference refer to like-numbered parts in the accompanying drawings. It is to be noted that the drawings are intended for the purpose of illustration only, and it is neither intended nor desired to limit the invention necessarily to the specific details of construction or ornamental design shown excepting insofar as they may be deemed essential to the invention.

Referring briefly to the drawings, Fig. 1 is a fragmentary perspective view of a structure including roof, ceiling and walls, formed of the flexible members of this invention.

Fig. 2 is a perspective view showing one of the flexible members in the various steps of the process installation in its final position on the building site.

Fig. 3 is a fragmentary cross-sectional elevational view of a structure utilizing a bow-string type of truss, wherein the top chord is made of one of the flexible members of this invention.

Fig. 4 is an enlarged fragmentary perspective view, partly in section and partly broken away,

showing the relationship between the top and bottom members and the webbing.

Fig. 5 is a fragmentary perspective view of a modified type of flexible member.

Fig. 6 is a fragmentary perspective view of another modified type of flexible member.

Fig. 7 is a front elevational view of a member of the type shown in Figs. 1 and 2 in its final position in the structure, not shown, but wherein the distance between the top and bottom elements of the member is less at its ends than at its middle.

Fig. 8 is a view similar to Fig. 7, but showing a member wherein the distance between the top and bottom elements is greater at the ends than at the middle of the member.

Fig. 9 is a view illustrating the manner of reinforcing a curved member at the top of the arch.

Figs. 10 and 11 illustrate different ways of bracing the curved member in its final position.

Referring in detail to the drawings, the numeral 15 indicates a fragment of a flexible member comprising a pair of spaced plates or elements 16 and 17 secured to opposite sides of a webbing 18, whereby the webbing retains the elements 16 and 17 in mutually spaced relationship. The securing of the plates 16 and 17 to the webbing may be achieved in any manner or by any means, such as, for example, welding, riveting, etc. The continuous length of the member 15 may be formed by welding or otherwise attaching together shorter lengths of material.

Fig. 5 shows a modified construction of the flexible member, herein indicated at 19, wherein, instead of the plates 16 and 17, horizontally spaced upper rods 20 form the upper element of the member, and similarly spaced lower rods 21 form the lower element. Webbing 22 joins the upper and lower elements in the same manner as above described, the rods 20 and 21 being secured, in any desired manner, to the corners of the webbing.

The form of flexible member shown in Fig. 6 at 23 has a single rod 24 constituting its upper element and a pair of horizontally spaced rods 25 forming its lower element. The upper and lower elements are joined by a triangular sectioned webbing 26 in the obvious manner illustrated.

In Fig. 2 a member 15 is indicated lying on the ground at the building site, and at 27 are shown sections of the foundation or wall tops on which the member is to be mounted and anchored. Prior to lifting the member 15 by securing the cable 28 of the boom 29 to its midpoint, cables 30 and 31 are secured to its ends: the latter cables pass

through a pulley block into the winding drum on the hoist 33, the pulley block being shown at 32. As the member 15 is lifted above the ground, by its midpoint, it will obviously sag at the ends, and with the cables 30 and 31 loose it will assume a position such as shown in broken lines at 15a. The amount of bend of the member may then be increased by drawing in the cables 30 and 31, and as the degree of flexing is increased the member will pass through the form shown at 15b and finally into that shown at 15c, that is, with the distance between its ends equal to that between the anchorages 27. The ends of the member bent into its final desired shape are then anchored in the anchorages 27 in any desired and well known manner. The flexing of the member into its final desired form may be achieved simultaneously while it is being maneuvered into position for anchoring it. However, the member may be flexed first and lifted into position afterward.

The structure shown in Fig. 1 illustrates the appearance of a structure consisting of a plurality of the member 15 erected and anchored in the manner just described above, wherein the bases, foundation, or wall tops are again indicated at 27. In this illustration, the top and bottom elements 16 and 17 of each member 15 but the forwardmost, are wider than the web 18 and extend to equal distances beyond the web, and the abutting edges or seams thus formed between adjoining upper elements 16 are shown at 34. Similarly, the seams thus formed by the lower elements 17 are shown at 35. The seams 34 and 35 are closed in any suitable manner, or, in other words, the abutting edges are all fastened together. The upper elements 16 thus together form the roof and the outer walls of the structure, and the lower elements 17 form the ceiling and inner walls. A door is shown at 36 and a window at 37. The designing engineer would understand how to frame around doors, windows, or other openings, as well as how to proportion the depth and cross-sectional area of the flexible members to preserve the smoothness of the curve wherever openings in the roof or walls occur.

In the diagrammatic view of the erected member 38 shown in Fig. 7, the distance between the upper member 16 and lower member 17 is at its maximum at the midpoint and uniformly diminishes toward both ends, at which points it is at a minimum. When such a member is flexed about its midpoint, it will attain the flattened arch shape illustrated.

In the member 39 of Fig. 8, the distance between the elements 16 and 17 is at its minimum at the midpoint of the member and increases uniformly toward both ends, at which it is at a maximum. Such a member, when flexed about its midpoint, will assume the pointed arch shape shown. Further variations of the flexibility and strength of the members may be achieved by varying the weight or cross-sectional areas of the top and bottom elements at different points along the curve. In Fig. 8, for example, it may be deemed desirable or necessary to increase the weight of the top and bottom elements at the thinnest section of the curve, and perhaps adjacent thereto also.

In large buildings it may be found necessary to brace the flexible members, and Figs. 10 and 11 illustrate schematically some examples of such bracing, but it is not deemed necessary to describe them in detail.

Fig. 9 illustrates a method of reinforcing a curved member at the top of the arch, that is, at the section most heavily stressed by the flexing operation. The member 15 is shown in its unflexed state in full lines, and in its final flexed condition in broken lines. In the latter condition it is brought into contact with the ends of the horizontal brace 40 which then becomes an integral part of the member, rendering it very much stronger and more rigid in its place in the structure.

The top and bottom elements 16 and 17, and the webbing 18, may all be made of the same material, such as steel, wood, fiber, plastics, plywood, glass, etc., or of any other useful material whatsoever. Or the said three elements which constitute the complete flexible member 15, may be each made of a different material, or any two thereof of one material and the third of another material.

Obviously, modifications in form and structure may be made without departing from the spirit and scope of the invention.

It should be mentioned that the thickness of the flexible members shown on the drawings is very greatly exaggerated both as a matter of necessity and to be able to illustrate the details of the members to better advantage. As an example of a closer approximation of the thickness of a flexible member with respect to its length, an erected flexible member having a span of one hundred feet and a height of fifty feet, would show a distance of but three or four inches between the top and bottom elements.

I claim:

The process of erecting large span buildings comprising the steps of forming an elongated continuous, hingeless flexible structural member, then lifting said member above a foundation and exerting a force to draw the ends of said member toward each other to curve said member and finally lowering said member on the foundation and anchoring the ends of said member thereto.

MICHAEL A. FOUHY.
